(57) **CLAIM**

The ornamental design for an electronic device, as shown
and described.

DESCRIPTION

FIG. 1 is a top, front, and side isometric view of a first
embodiment of an electronic device embodying the new
design;

FIG. 2 is a bottom, back, and side isometric view thereof;

FIG. 3 is a front view thereof;

FIG. 4 is a back view thereof;

FIG. 5 is a first side view thereof;

FIG. 6 is a second side view thereof;

FIG. 7 is a top view thereof;

FIG. 8 is a bottom view thereof;

FIG. 9 is a cross-sectional view along lines 9-9 in FIG. 7;
and

FIG. 10 is a detail view of area 10 in FIG. 9.

FIG. 11 is a top, front, and side isometric view of a second
embodiment of an electronic device embodying the new
design;

FIG. 12 is a bottom, back, and side isometric view thereof;

FIG. 13 is a front view thereof;

FIG. 14 is a back view thereof;
